UNITED STATES PATENT OFFICE.

FRANK W. LINCOLN, OF BANGOR, MAINE.

BROOM-HANDLE ATTACHMENT.

SPECIFICATION forming part of Letters Patent No. 277,298, dated May 8, 1883.

Application filed September 5, 1882. (No model.)

To all whom it may concern:

Be it known that I, FRANK W. LINCOLN, of Bangor, in the county of Penobscot and State of Maine, have invented certain new and useful Improvements in Attachments for Broom-Handles and like Articles; and I do hereby declare that the following is a full, clear, and exact description of the invention, that will enable others skilled in the art to which it appertains to make and use the same, reference being had to the accompanying drawings, forming a part of this specification, in which—

Figure 1 shows a section of my invention; Fig. 2, a side view of the same suspended in a broom-hanger.

Same letters show like parts.

My invention consists of an improved attachment for the handles of brooms, hoes, and like articles. It is designed to avoid the friction against the hand of the operator and at the same time to afford a means by which the implement may be suspended when not in use.

Reference to the drawings will explain my invention fully.

At *a* is shown a portion of the upper end of a broom-handle.

b shows a cup or socket, which, for economy, may be made of wood, loosely fitting over the end of the handle and held thereto by a screw or nail, *c*, passing through the opening in the top of the cup or socket and into the handle. The head of the screw or nail *c* is countersunk in the top of the cup, which latter revolves around it as on a pivot, thus affording a smooth

rotating sleeve, completely covering the upper end of the broom-handle. As the cup or socket *b* is larger in diameter than the broom-handle, it projects at its lower end, and thus serves as a means by which the broom may be suspended in any of that class of broom holders or hang-

ers in which the broom-handle is inserted between the jaws of a yoke or clamp—as, for instance, as shown in Fig. 2.

My device also tends to prevent the side-wise wear of a broom, the rotary motion of the handle tending to make all the parts wear equally.

I do not claim the device shown in the patent of P. Lamboy, August 27, 1878, No. 207,427, which consists of a cylindrical sleeve retained in place on the broom-handle by means of a screw-eye passing through a non-rotating button, said screw-eye serving to suspend the broom; nor do I claim the device shown in Wagner's Patent No. 239,126, consisting of a knob attached to the broom-handle but not rotating thereon.

My device is a cup or thimble covering entirely the head of the broom, adapted to rotate easily thereon, and by means of its greater diameter affording a support for the broom when hung up, without interfering with the round and rotating surface required by the hand of the operator. These features are not combined in either of the references given.

What I claim as my invention is—

In combination with the handle of a broom or like article, the cup or socket *b*, of greater diameter than said handle, and completely enclosing the upper end of the same, secured thereto by a screw or nail, *c*, serving as a pivot, around which it rotates freely, substantially as herein set forth and described.

In testimony that I claim the foregoing I have hereunto set my hand this 1st day of July, 1882.

FRANK W. LINCOLN.
